(Cl. D56—4)

To all whom it may concern:

Be it known that we, Robert Cooper Scull and Jacques Martial, citizens of the United States and residents of the city, county, and State of New York, have invented a new, original, and ornamental Design for a Radio Receiver Cabinet or the like, of which the following is a specification, reference being had to the accompanying drawing, forming part thereof, in which:

Fig. 1 is a perspective view of a radio receiver cabinet or the like embodying our design.

Fig. 2 is a section taken along lines 2—2 of Fig. 1.

The characteristic features of our design are shown by means of full lines in the drawing.

We claim:

The ornamental design for a radio receiver cabinet or the like, as shown and described.
